UNITED STATES PATENT OFFICE

2,579,054

APPARATUS FOR PRESSING OUT LIQUID

Ray W. Scott, Los Angeles, Calif.

Application December 28, 1944, Serial No. 570,128

7 Claims. (Cl. 15—261)

1

This invention relates to apparatus for removing or expressing excess liquid from articles, such as mops, or swabs, or the like.

As is well understood in the use of a mop, the mop usually is made as wet as desired by immersing the mop in water, or an appropriate liquid mixture, commonly provided in a portable container, such as a bucket, or tub, and then pressing or wringing the mop to remove the surplus liquid. It is an object of this invention to provide an improved unitary structure, comprising a container for the liquid mixture, and means for removing surplus liquid from the mop.

It is another object of this invention to provide improved pressing or wringing means for removing liquid from a mop, swab, or the like.

It has been common in the past to provide a pair of wringer rolls, supported on the container, for operating on the mop; but such provisions are ineffective, for the mop retains a large amount of moisture.

It is, accordingly, another object of this invention to provide a wringing or pressing device, or the like, which is readily operable to exert considerable pressure, and thereby to provide a much drier mop than has been possible by the use of the common wringer rolls.

It is still another object of this invention to provide a hydraulically operated wringing or pressing mechanism, and especially one that is operated manually.

It is a still further object of this invention to provide a hydraulic pressure pump having novel means for releasing the pressure when desired.

This invention possesses many other advantages, and has other objects which may be made more clearly apparent from a consideration of a few embodiments of the invention. For this purpose there are shown several forms in the drawings accompanying and forming part of the present specification. These forms will now be described in detail, illustrating the general principles of the invention; but it is to be understood that this detailed description is not to be taken in a limiting sense, since the scope of this invention is best defined by the appended claims.

Referring to the drawings:

Figure 1 is an elevation of a device incorporating the invention;

Fig. 2 is a plan view thereof;

Fig. 3 is a vertical section on an enlarged scale, taken along plane 3—3 of Fig. 1;

Fig. 4 is a detail section of a fragment of Fig. 55

2

3, showing a different operating position of the parts;

Fig. 5 is a detail cross section, taken on plane 5—5 of Fig. 3;

Fig. 6 is a view, partly in section, taken along plane 6—6 of Fig. 3;

Fig. 7 is a fragmentary view, similar to Fig. 6, but showing a different operating position of the parts; and

10 Fig. 8 is a view similar to Fig. 6, but showing a modified form of the invention.

The device is shown (Figs. 1 and 6) as comprising a container or bucket 1, which may be of light sheet metal and, preferably, of elongated cross section. The squeezing or wringing mechanism 2 is mounted near one end of the bucket 1, and includes a tubular housing 3 open at both ends and supported above the bottom of the bucket 1 by a number of columns or posts

4. A pressure member 5 (see, also, Fig. 3) is arranged for longitudinal movement within housing 3 by hydraulically operated mechanism 6, and serves to support the article from which the liquid is to be expressed, such as a mop or swab, within the housing 3, as shown in Fig. 7. As the member 5 moves upwardly, a pair of gates 7 and 8 pivotally mounted on the housing 3 are swung to close the top of the housing by the cam mechanism 9 (Fig. 6). In this position, the gates 7 and 8 serve to restrain upward movement of the article so that, as member 5 continues to move up, the article is confined between member 5 and gates 7 and 8, the pressure exerted thereby serving to express or wring a substantial part of the liquid from the article.

The hydraulic mechanism 6 is actuated by a pressure pump 10 (Figs. 1 and 3) attached to the outside of the bucket 1 and arranged to be operated by the user's foot. In this way considerable pressure may be exerted readily on the mop; and it is an easy matter to wring it as dry as desired. Means are provided whereby appropriate manipulation of the plunger of pump 10 releases the pressure in the hydraulic mechanism 6 so that member 5 and gates 7 and 8

45 may be returned to their initial position and the mop freed for removal and use. As shown, the mechanism 6 is actuated by liquid taken from the bucket 1 and returned there after use; but, if desired, liquid may be taken from another source for this purpose.

The apparatus will now be described in detail. The housing 3 has a cylindrical portion 15 with an annular flange 16 about its lower edge, which is suitably secured to the tops of the columns, 4.

The pressure member 5, which supports the mop, is dished and provided with a cylindrical rim 17 which is freely slideable in housing 3 (see Fig. 3). Thus, member 5 resembles a piston and may be described as a piston-like member. Member 5 is secured to the upper end of the piston rod 18 of the hydraulic mechanism 6, as by a screw 19. Interposed between rod 18 and member 5 is the cam member 20 (Figs. 3, 6, and 7) which forms one element of the cam mechanism 9; and a reinforcing plate 21. The piston rod 18 is attached to a piston 22, as by a screw 23. Piston 22 is slideable in a cylinder 24 and is packed by a conventional cup leather 25. Cylinder 24 may comprise a tube threaded at its lower end 26 into a base 27 which cooperates with the cylinder 24 and the piston 22 to form a closed pressure space 28.

The base 27 is provided with a plurality of legs 29 having flat feet or pads 30 which support the cylinder 24 on the bottom 1-a of the container 1. For this purpose, the bottom 1-a is provided with a plurality of intruded portions 32, there being one of these for each leg 29. The posts 4 are respectively supported on the pads 30, a single screw 33 in each post serving to hold the post 4 and pad 30 in assembled relationship on the pressed portion 32 (see Fig. 6). Suitable washers, as 34, are provided between the head of screw 33 and the bottom 1-a of the container 1 to prevent leakage. A port 36 is provided in head 27 leading into the pressure space 28 and communicating with the pump 10 by conduit 37.

The gates 7 and 8 are substantially identical, each comprising an element 40 in the form of a circular arc, which embraces the housing 3. The gates 7 and 8 are pivotally secured to the tubular part 15 of housing 3 by pintles 43 and 44, and are adapted to swing upwardly about their pintles from the position shown in Fig. 6 to that shown in Fig. 7. For this purpose, cam following rollers 45 and 46 are mounted respectively on the extremities or side walls 41 and 42 of each element 40.

Cam member 20 extends across and beneath housing 3. The cam member 20, which is exterior of cylinder 24, is provided with downward offsets 47 terminating in upwardly directed fingers 48, each finger having cam surfaces 49 and 50 on its opposite edges, the upper end portions 49-a and 50-a of these cam surfaces being inclined toward each other.

From an inspection of Figs. 6 and 7, it will be clear that gates 7 and 8 tend to swing downwardly about their pintles 43 and 44 in response to gravity, thereby urging cam followers or rollers 45 and 46 against cam surfaces 49 and 50. With cam member 20 in its lowermost position, as shown in Fig. 6, rollers 45 and 46 engage the upper end portions of the inclined surfaces 49-a and 50-a, allowing gates 7 and 8 to assume a position in which they entirely uncover housing 3.

As cam member 20 is moved upwardly by piston 22, in response to pressure in chamber 28, the inclined surfaces 49-a and 50-a urge rollers 45 and 46 apart, swinging gates 7 and 8 together above the housing 3. With the rollers 45 and 46 in this position, they are spaced sufficiently far apart to permit fingers 48 to pass between them, the rollers, by engaging the straight portions of cam surfaces 49 and 50, serving to maintain the gates 7 and 8 in this position (see Fig. 7) even after the cam fingers 48 continue their upward movement. Thus, the gates 7 and 8 cooperate with the member 5 to exert pressure on an object, such as a mop, in the housing 3 as member

5 moves upwardly in response to pressure in chamber 28. Upon release of the pressure in chamber 28, piston 22, member 5, and cam member 20 may be returned to their lower or initial positions by downward pressure exerted on the mop handle by the user. This allows gates 7 and 8 to return to their initial positions by gravity and to uncover the housing 3.

An important detail of this construction is that the rollers 45 and 46 and fingers 48 cooperate with piston 22 properly to guide the piston 22 and cam member 20 in their upward movement. For this purpose rollers 45 and 46 are provided with grooves 45-a and 46-a to accommodate the fingers 48 (see Figs. 3 and 7).

The pump 10 for controlling the pressure in chamber 28 comprises a cylindrical barrel 55 (Figs. 1 to 5) threadedly secured at its lower end 56 in a base block 57, attached to an appropriately flattened portion 58 on the exterior of the vertical wall 1-b of the bucket 1. For this purpose a screw plate 59 is provided on the inside of the bucket portion 58, which is threadedly engaged by screws 60 passing through the base block 57 and bucket wall 1-b. Suitable gaskets 61 and 62 are provided to prevent leakage of liquid around block 57.

A pair of spaced vertical guide rods 64 and 65 extend upwardly from block 57, their upper ends being supported by a bracket 66 secured on wall 1-b (see Figs. 1, 2, and 3). A packed plunger 67 is reciprocable within barrel 55, being joined with a foot pad 68 by a piston rod 69. The foot pad 68 embraces rods 64 and 65 so as to be guided thereby, and is normally urged to the upper limit of its movement by compression springs 70 and 71 encircling rods 64 and 65 respectively and supported by suitable stops 72 on the rods. These stops 72 may be formed conveniently by cotter pins passed through suitably positioned apertures in the rods.

The arrangement is such that downward movement of the pad 68 and plunger 67, as by the pressure of the user's foot, forces liquid from pump barrel 55 through conduit 37 into the pressure space 28. Upon relaxation of the pressure on pad 68, springs 70 and 71 are effective to urge pad 68 and plunger 67 upwardly to their initial position, liquid being drawn into cylinder 55 from the container 1. A subsequent depression of the pad 68 and plunger 67 forces this additional liquid into space 28, which, in turn, forces piston 22 and connected parts additionally upwardly. This cycle may be repeated as often as necessary to cause the pressure member 5 to exert a desired pressure on the mop confined by gates 7 and 8 in housing 3. Care must be exercised, however, so that plunger 67 is not depressed to its lower limit of movement, at least not more than momentarily, since means are provided whereby retention of the plunger in such position permits discharge of liquid from space 28.

The means by which movement of the pump plunger accomplishes these results will now be described. Referring to Fig. 4, it will be seen that block 57 has a valve chamber 75 formed therein, opening at the bottom of block 57 and closed by a threaded plug 76. This chamber is in communication with the interior of bucket 1 by a port 77 which extends through plate 59 where it connects with a conduit 78 leading to a fine mesh tubular screen 79 (see Fig. 2).

An inlet port 80 leads from chamber 75 to the interior of barrel 55, terminating in a portion 81 of enlarged diameter, whereby a valve seat

82 is formed. A ball valve 83 cooperates with seat 82 to permit liquid to pass from chamber 75 into cylinder 55 and to prevent reverse flow of liquid. A screw 84 is threaded into block 57 adjacent port 80 so that its head overhangs the enlarged portion 81 of the port, thus serving to limit upward movement of ball valve 83 (see, also, Fig. 5).

An outlet port 86 leads from the interior of barrel 55 and is connected with valve chamber 75 by an enlarged intermediate port 87 forming a valve seat 88 controlled by a ball valve 89. A port 90 connects port 87 with conduit 37. A by-pass valve seat 91 is formed between port 87 and valve chamber 75 and is axially spaced from the outlet valve seat 88. Seat 91 is axially aligned with port 87, and faces the same way as seat 88. The valve seat 91 is controlled by a ball valve 92, urged toward seat 91 by a compression spring 93 seated in plug 76. A spring 94, confined between ball valves 89 and 92, similarly urges ball valve 89 toward its seat.

Plunger 67 is of conventional design, comprising a pair of oppositely facing cup leathers 100 and 101 secured in assembled relationship on rod 69 by a nut 102 threaded on the end of rod 69. This nut has a flat outer face 102-a adapted to engage the surface of block 57 within barrel 55, thereby limiting downward movement of the plunger 67 and pad 68.

Further, rod 69 has an extension 103 of reduced diameter adapted freely to enter port 86 and contact ball valve 89. The parts are so proportioned that, when plunger 67 is at the lower limit of its movement, ball 89 is unseated (in a downward direction) a sufficient distance also to unseat the by-pass valve 92. Liquid can then pass freely from the pressure space 28, through conduit 37, ports 90 and 87, past valve 92 to port 71, and thence through conduit 78 and screen 79 into bucket 1. Thus, by depressing pad 68 to its lower limit, pressure member 5 is permitted to return to its initial position.

As long as plunger 67, in its downward movement, is not depressed sufficiently for extension 103 to cause unseating of the by-pass valve 92, this valve serves merely as a safety or relief valve, since spring 93 is sufficiently strong to maintain it seated during normal operation of the pump. However, brief consideration will show that a pressure sufficiently great to damage various parts of the mechanism may be built up by improper operation of the pump. When an excessive pressure is thus created, valve 92 will unseat against the force of spring 93 and by-pass liquid to the bucket to relieve the excess pressure.

The operation of the device may now be set forth in more detail. With the pressure member 5 in its lower position, and gates 7 and 8 in position to uncover housing 3, the mop or swab which it is desired to wring or press is placed within container 3 and on member 5, the handle of the mop or swab being held approximately vertical. The pad 68 is then operated a number of times, as required, to cause, first, upward movement of member 5 and connected parts to swing gates 7 and 8 to closed position, confining the mop against the pressure member 5, and then to cause member 5 to exert a suitable pressure against the mop to express the liquid therefrom. The parts will then be in substantially the relative positions illustrated in Fig. 7. The gates 7 and 8 have central cut-out spaces 7-a and 8-a to accommodate the mop handle at this time. A plurality of openings 5-a are provided in the bottom of member 5 to facilitate the escape of liquid therefrom.

When a desired amount of liquid has been expressed from the mop, plunger 67 is depressed to the limit of its movement, allowing the liquid to escape from pressure space 28, which, in turn, allows pressure member 5 and gates 7 and 8 to return to their initial position. The mop can then be readily removed from the container 3.

Although the housing 3 is shown as of circular cross section, it is to be understood that it may have a cross section of some other shape, such as square or rectangular, if desired, to suit differently shaped articles from which it is desired to express liquid.

The terms "wringing," "wringer mechanism," and the like, which appear in the specification and claims are not to be construed as necessarily including a twisting or rotary movement to express the liquid from the mop or other article, but to refer generally to a pressing or squeezing operation for such purpose.

In the modified form of the invention shown in Fig. 8, an apparatus is disclosed which is substantially identical with that just described except for the mechanism which operates the gates 7 and 8. Thus, there is the tubular housing 3 supported by posts 4, into which the pressure member 5 is urged by fluid pressure supplied to cylinder 24 by conduit 37, all as before.

In place of the cam mechanism of the prior form, an auxiliary cylinder 110 is provided for urging gates 7 and 8 to closed position above housing 3. This cylinder 110 is shown as formed by a short tube 111 threadedly secured on the upper side of a supporting bridge 112, extending between an adjacent pair of the posts 4 and secured thereto. For this purpose, the bridge 112 is provided with bosses 113 respectively at its opposite ends through which the posts 4 pass, a taper pin 114 axially fixing the posts in the bosses.

A conventional piston or plunger 115 is provided in tube 111 and cooperates therewith to define a pressure space 116 which is in continuous communication with conduit 37 by a branch conduit 117. Piston 115 carries a yoke 118 by means of a short piston rod 119. Links 121 and 122 are pivoted at the opposite ends of yoke 118 and extend upwardly therefrom to gates 7 and 8 respectively, link 121 being pivotally secured at 123 to side member 41 of gate 7, and link 122 being pivotally secured at 124 to side member 42 of gate 8. Compression springs 125 and 126, surrounding links 121 and 122, are interposed between flange 16 and yoke 118, serving to urge yoke 118 to its lowermost position in which it seats on top of tube 111 and swings gates 7 and 8 clear of the opening in housing 3.

It will be apparent that pressure in space 118 sufficient to overcome the force of springs 125 and 126 will urge piston 115 and connected parts upwardly and swing gates 7 and 8 together to close the top of housing 3; in the same manner as shown in Fig. 7. Release of this pressure permits springs 125 and 126 to return the piston to its lower position.

Such actuating pressure in space 116 is obtained by operating the pump 10 and restraining upward movement of pressure member 5, as by downward force exerted on the mop handle. This will cause the pressure built up in conduit 37 and pressure chamber 28 in the main cylinder 24 to act in space 116 by connection 117.

The inventor claims:

1. In a wringer mechanism, a housing open at both ends, a pressure member movable longitudinally in the housing, means for moving said member in pressure exerting direction, means in-

cluding a gate element pivoted on the housing for movement transversely of the housing, to close that end of the housing toward which said member moves in a pressure exerting operation, means forming a cam surface on said member, and means forming a cam follower on said element cooperating with said cam surface, said surface being so formed as to move said element to closed position in response to an initial portion of the movement of said member in pressure exerting direction, and to maintain said element in closed position during the balance of the movement of said member in pressure exerting direction.

2. In a wringer mechanism, a housing open at both ends, a pressure member movable into the housing from one end thereof, means for moving said member in pressure exerting direction, a pair of gate elements pivoted at spaced points on the housing for movement in opposite directions transversely of the housing to close the other end of the housing, a pair of spaced cam followers respectively on said gate elements, and means forming a wedge-shaped cam surface carried by said member interposed between said followers, whereby movement of said member in pressure exerting direction causes said elements to move in closing direction.

3. In a wringer mechanism, a housing open at both ends, a pressure member movable into the housing from one end thereof, means for moving said member in pressure exerting direction, a pair of gate elements, each embracing the housing and being pivotally secured on opposite sides thereof, pairs of spaced cam followers respectively on said elements on opposite sides of the housing, and a cam member carried by said member having fingers respectively on opposite sides of the housing, each of said fingers having a wedge-shaped cam surface interposed between the cam followers of each pair of cam followers, whereby movement of said member in pressure exerting direction causes said elements to move in closing direction, said cam followers cooperating with said fingers to guide the means moving said member.

4. In a liquid expressing mechanism: a housing open at its opposite ends; a pressure applying member in the housing; an axially movable rod connected to the member for applying a force thereto; a pair of covers, each pivoted on opposite walls of the housing, for closing one end thereof; and a cam member carried by the rod for moving said cover members to closed position, said cam member having cam carrying arms respectively at opposite sides of the housing, and assisting in guiding the motion of the rod.

5. In combination: a liquid container, and a pressure exerting device adapted to express liquid from a mop or the like into said container, said device comprising: a stationary tubular housing for said mop or the like; a pair of gates, each rotatable about separate fixed points of said housing, said gates being capable of closing one end of said stationary housing and providing

thereby a surface against which the mop may be pressed; a presser member adapted to be moved longitudinally of said stationary housing toward and away from said gates; fluid pressure means utilizing the liquid of said container for moving said presser member and for rotating said gates; and means conducting the liquid of said container to said fluid pressure means including a plunger adapted to be manually operated exteriorly of the container.

6. In combination: a liquid container, and a pressure exerting device adapted to express liquid from a mop or the like into said container, said device comprising: a stationary tubular housing for said mop or the like; a pair of gates, each rotatable about separate fixed points of said housing, said gates being capable of closing one end of said stationary housing and providing thereby a surface against which the mop may be pressed; a presser member adapted to be moved longitudinally of said stationary housing toward and away from said gates; means providing a cammed surface movable with said presser member; and a cam follower carried by each of said gates.

7. In combination: a liquid container, and a pressure exerting device adapted to express liquid from a mop or the like into said container, said device comprising: a stationary tubular housing for said mop or the like; a pair of gates, each rotatable about separate fixed points of said housing, said gates being capable of closing one end of said stationary housing and providing thereby a surface against which the mop may be pressed; a presser member adapted to be moved longitudinally of said stationary housing toward and away from said gates; means forming a cammed surface movable with said presser member; a cam follower carried by each of said gates; fluid pressure means utilizing the liquid of said container for moving said presser member; means conducting the liquid of said container to said fluid pressure means; a plunger adapted to be manually operated exteriorly of said container for actuating said fluid pressure means; and manually operable means whereby liquid is entirely removed from said presser means.
